UNITED STATES PATENT OFFICE.

JOHN SORENSEN, OF CHICAGO, ILLINOIS.

WALL-BED.

1,349,738.

Specification of Letters Patent. Patented Aug. 17, 1920.

Application filed August 10, 1916. Serial No. 114,134.

To all whom it may concern:

Be it known that I, JOHN SORENSEN, a citizen of the United States, and a resident of the city of Chicago, county of Cook, and

5 State of Illinois, have invented certain new and useful Improvements in Wall-Beds, of which the following is a specification.

My invention relates to improvements in wall beds, and has for its object the provision of an improved construction of this 10 character which is simple and efficient in operation.

The invention consists in the combinations and arrangements of parts hereinafter 15 described and claimed.

The invention will be best understood by reference to the accompanying drawings forming a part of this specification, and in which,

20 Figure 1 is a top plan view shown partially in section, of a wall bed construction embodying my invention,

Fig. 2, a vertical longitudinal section of the same,

25 Fig. 3, a section taken on line 3—3 of Fig. 2,

Fig. 4, a transverse section of the construction looking toward the wall,

30 Fig. 5, a detail view illustrating means employed for locking supporting legs employed in the construction, in operative position, and

35 Fig. 6, a detail view illustrating means employed for locking said legs in folded position.

The preferred form of construction, as illustrated in the drawings, comprises a recess or compartment 7 provided in a wall of a size adapted to receive the bed construction folded upwardly. The opening in the 40 compartment 7 is closed by a panel or wall section 8 which is pivoted centrally on trunnions 9 to revolve on a vertical axis. Substantially L-shaped brackets 10 are secured 45 to the inner face of panel 8, and are connected at their outer ends by means of a cross channel bar 11, as indicated. Two substantially U-shaped bell crank levers 12 are pivotally mounted at the lower ends of 50 the brackets 10 and are connected by a cross bar 13, as shown. One arm of each of the bell cranks 12 is connected by means of links 14 and 15 with the corresponding bracket, 55 said links being pivotally connected at 16 to form a "knee" joint and serving to guide said bell cranks in their motions. Tension

springs 17 are also connected between the corresponding ends of the bell cranks 12 and the corresponding brackets 10, as indicated.

60 A suitable bed frame construction 18 is pivotally mounted on a cross rod 19 extending between the upper ends of the bell cranks 12. The head of the bed construction is formed in two parts 20 and 21, the part 65 20 being rigidly secured to the bed frame construction 18, and the portion 21 being hinged at 22 to the portion 20. The upper portion of the head portion 21 is connected by a pivoted link 23 with the panel 8 so as 70 to cause automatic folding thereof when the bed frame construction 18 is swung upwardly against said panel.

The foot portion 24 of the bed is rigidly connected with the bed frame construction 75 18 and supporting legs 25 are pivotally connected therewith and connected by means of a cross frame 26, said supporting legs 25 folding and unfolding automatically under the influence of gravity, as will be readily 80 understood, and the hinge being constructed as indicated, to limit the swing of said legs in one direction. A vertically slidtable angular locking member 27 is provided for locking the legs 25 in extended or operative 85 positions, and locking fingers 28 having hooks 28' are provided for locking said legs in folded position, as indicated.

Two substantially U-shaped links 29 are pivotally connected at one end with a cross 90 bar or rod 30 of the bed frame construction and at their other ends are pivoted at points 31 to the corresponding brackets 10, the arrangement being such that, as the bed frame construction is swung upwardly, the rod 30 95 crosses the arc in which the rod 19 swings, thus passing the line of dead center, so that the tension of spring 17 tends to automatically fold the bed frame 18 upwardly after said line or dead center has been crossed. 100 Before such crossing the springs 17 tend to automatically draw the bed frame construction downwardly into extended position. Thus in upward folding of the bed the cross rod 19 first swings outwardly while 105 the rod 30 swings downwardly and outwardly until the arc of swing of the rod 30 crosses the arc of swing of the rod 19, whereupon tension in spring 17 causes the rod 19 to swing inwardly thus assisting in 110 the upward folding of the bed. In downward folding of the bed these motions and actions

of the parts are reversed. Cushion springs 32 are connected with rod 30 and with the cross bar 11 so as to cushion the downward movement of the bed frame construction and prevent accidents or jars from too sudden opening of the same.

In use, when it is desired to use the bed, the panel 8 is swung on its pivot to bring the bed construction out into the room when 10 the same may be readily lowered into operative relation. When it is desired to dispose of the bed, the same is swung upwardly to the position indicated by the dotted lines in Fig. 2 and the panel 8 swung on its pivot 15 to carry the bed construction into the recess or compartment 7.

The specific form and arrangement of the parts set forth is a simple and efficient one for the purpose.

20 While I have illustrated and described the preferred form of construction for carrying my invention into effect, this is capable of variation and modification without departing from the spirit of the invention. I, 25 therefore, do not wish to be limited to the precise details of construction set forth, but desire to avail myself of such variations and modifications as come within the scope of the appended claims.

30 Having described my invention what I claim as new and desire to secure by Letters Patent is:

1. The combination of a support; and a

bed construction pivoted for folding upwardly against said support, said bed construction being pivotally mounted on two swinging members to cause the arcs of swing of the pivotal mountings of the bed construction to cross each other; and a spring operatively connected with one of said 40 swinging members and arranged to operate to yieldingly hold said bed construction in both its folded and unfolded condition, substantially as described.

2. The combination of a support; a pair 45 of substantially U-shaped bell crank levers pivoted on said support; a bed construction pivotally mounted on one set of arms of said levers; springs connected with the other arms of said levers; and a pair of substantially 50 U-shaped links pivotally mounted at one of their ends on said support, the other ends of said links being pivotally connected with said bed construction, the pivoted connections of said links and said levers with 55 said bed construction being arranged to swing on arcs which cross each other as said bed construction is folded, substantially as described.

In testimony whereof I have signed my 60 name to this specification in the presence of two subscribing witnesses.

JOHN SORENSEN
